UNITED STATES PATENT OFFICE.

JOSEPH S. WOOD, OF BROOKLYN, NEW YORK.

GAS-MACHINE.

SPECIFICATION forming part of Letters Patent No. 289,593, dated December 4, 1883.

Application filed August 28, 1883. (No model.)

To all whom it may concern:

Be it known that I, JOSEPH S. WOOD, of Brooklyn, in the county of Kings and State of New York, have invented certain new and 5 useful Improvements in Gas - Machines, of which the following is a specification.

This invention relates to certain improvements in automatic gas apparatus of that class in which the vapors are generated from light 10 hydrocarbons by means of heat; and the invention consists, first, in a novel combination of parts for actuating the needle-valves of the mixing-chamber and of the burner that heats the retort with a gas-holding drum, so as to 15 automatically regulate the operation of the machine by the rise or fall of the drum, according to the gas consumed.

The accompanying drawing represents a 20 vertical longitudinal section of my improved gas-machine.

A represents a gas-generating retort, of cylindrical or other shape, which is provided at its bottom with a downwardly-extending perforated flange, a. A gas-burner is arranged 25 below the retort, and supported by a downwardly-extending gas-pipe, b, that communicates by a small gas-supply opening, b', with the lower part of the gas-burner B, said opening being opened or closed by means of a horizontal needle-valve, b''. The gas-burner B is 30 further provided with a vertical needle-valve, B', that opens or closes an opening, d, leading to the mixing-chamber of the burner, which mixing-chamber has an air-port, d', as customary in vapor-burners of this class. The 35 needle-valve B' is pivoted at its lower end to a sleeve, e, that is applied by a set-screw, e', to the end of a fulcrumed lever, C. The opposite end of the lever C is connected by an 40 intermediate pivot-link, C', with a lever, D, that is fulcrumed to supporting-arms D, secured rigidly to the top of the retort A. The 45 opposite end of the lever D is connected to a vertical rod, f, of the drum F of a gas-holder, F'. The rod f is guided in eyes of fixed brackets f' of the lower part of the holder F', and provided with screw-nuts f'', between the brackets, which screw-nuts are adjustable higher or lower on the threaded middle portion of the guide-rod f. The gas - holder is 50 constructed, in the usual manner, with a condensing - chamber, F², at the lower part, to

which the gas-main that leads to the burners is connected. An upright pipe, g, extends from the condensing - chamber F² into the 55 drum, so as to supply the gas to the drum at a point above the level of the water used for sealing the drum. The retort A is connected by a short pipe, a', to a valve-chamber, E, the conical ejection-opening i of which is closed 60 or opened by a needle-valve, E', the outer end of which is connected, by a slotted strap, E², having a stop-screw, h, at its upper part and a knife-edge, h', at its lower part, to the shorter arm of the fulcrumed lever D. The valve-chamber E communicates by the opening i with a mixing-chamber, G, in which the vapors generated in the retort are mixed with 65 atmospheric air drawn in through an air-port, i. The mixed vapors and air are forced 70 through the injection-throat i² into a connecting gas-pipe, i³, and thence conducted to the condensing-chamber F² at the lower part of the gas-holder F'. The naphtha or other light 75 hydrocarbon is conducted from the oil-tank to the retort A by a valved pipe, H, in which it is forced to ascend to the retort by suitable air-pressure. The connecting-lever D is provided below its fulcrum with a beveled projection or trip, m, that is acted upon by a 80 band-spring, m', attached to the top of the retort A. The spring m' assists in quickly opening or closing the needle-valves of the mixing-chamber and burner when the point of the trip m has passed to one side or the other 85 of a vertical line passing through the fulcrum of the lever D. When the drum F, after having been filled with gas, gradually falls, so that the trip m of the lever E passes the center line of its fulcrum, the action of the spring 90 on the trip m produces the quick downward motion of the lever E, which opens the needle-valves of the mixing-chamber and burner to their full extent, so as to enlarge the heating-flame and cause the generation of a larger 95 quantity of gas. When, however, by the rise of the drum F, the trip passes through the center of the fulcrum in opposite direction, the action of the spring imparts at that moment a quick motion to the lever D and to 100 the needle-valves of the mixing-chamber and burner, so as to quickly reduce thereby the size of the heating-flame and diminish thereby the supply of gas to the drum F. The al-

ternate rising and falling of the gas-drum regulates in this manner automatically the generation of gas in the retort. The apparatus works, however, also in a reliable and automatical manner without the spring m' , owing to the connection of the gas-drum with the fulcrumed lever D and the needle-valves of the mixing-chamber and burner, as the drum, and consequently the lever E , will rise or fall with the varying consumption of gas, and thereby close or open the needle-valves, so that a quantity of gas corresponding to the number of burners in use is generated in the retort. The regulating trip and spring, however, have the advantage that at certain positions of the gas-drum the generation of gas will be quickly increased or diminished, as the machine responds thereby more effectively to the requirements.

The operation of the apparatus is as follows: The oil-tank is filled with oil that is placed under air-pressure therein, so that the oil will pass through the supply-pipe H into the retort. The burner B is first heated up for starting the apparatus by alcohol that is burned in a cup at the lower part of the burner B . The horizontal needle-valve of the burner B is next opened, so that some of the oil can pass through the burner, where it is mixed with air and ignited. The flame of the burner then heats gradually the retort and generates vapors therein, which keep up continuously the flame of the burner B by means of the connecting-pipe b , while the greater portion passes through the valve-chamber E into the mixing-chamber G , where they are mixed with atmospheric air, and then conducted through the pipe i^3 to the gas-drum F , from which the burners are supplied with gas. The generation of vapors in the retort is diminished as the drum rises by the action of the intermediate lever mechanism, and increased when the drum falls and the gas is consumed by the burners. When the apparatus is properly started and regulated, it requires no further attention, as all the different operations are accomplished automatically.

My improved automatic gas-machine is of simple construction, and can be furnished at a comparative small expense. It works with great regularity and precision, and supplies illuminating-gas in sufficient quantity as required by the number of gas-burners thrown into use. When some of the gas-burners are extinguished, the generation of gas is automatically diminished, and increased when a larger number is lighted.

I am aware that gas-machines of that class in which the mixing-chamber of the retort, the burner of the retort, and the valves of a system

of gas-conducting pipes are connected by a suitable lever mechanism with the gas-holder are not new, and I therefore do not claim these features. In these gas-machines the burner of the retort is supplied with gas from the gas-holder or from the mixing-chamber of the retort, according to the position of the gas-holder, whereby the generation of gas in the retort is automatically controlled. This is different from my method of automatically controlling the generation of gas, as in my machine the burner is not connected to the gas-holder and supplied with gas therefrom, but connected to the retort, so as to receive its gas-supply directly from the same. The generation of gas is controlled by the rise or fall of the gas-holder, which is connected by intermediate lever mechanism with the valves of the mixing-chamber and burner, whereby the generation of gas is regulated in a very simple and effective manner.

Having thus described my invention, I claim as new and desire to secure by Letters Patent—

1. The combination of a generating-retort, a burner connected by a valved gas-pipe to the retort and provided with a gas and air mixing chamber, a vertically-sliding needle-valve of the burner, a mixing-chamber connected to the retort and having a needle-valve, a gas-holder having a vertically-movable gas-drum, and actuating-lever mechanism that connects the drum with the needle-valves of the burner and mixing-chamber, whereby the generation of the gas is automatically controlled by the rising or falling of the drum, substantially as set forth.

2. The combination of a generating-retort, A , a burner, B , for heating the same, a needle-valve, B' , of the burner, a mixing-chamber, G , a needle-valve, E' , of the same, actuating-levers C and D , connected to the needle-valves of the burner and mixing-chamber, and a gas-drum, F , connected to the lever D , substantially as set forth.

3. The combination of a generating-retort, A , needle-valves B' and E' of the burner and mixing-chamber, fulcrumed and connected levers C and D , and a gas-drum, F , having a guide-rod, f , with adjustable screw-nuts f' , the lever having a tapering trip, m , that is engaged by a spring, m' , substantially as set forth.

In testimony that I claim the foregoing as my invention I have signed my name in presence of two subscribing witnesses.
